DRAFT CONTROL

Edward A. Field, Jr., Chicago, Ill.

Application February 24, 1941, Serial No. 380,095

16 Claims. (Cl. 236—45)

This invention relates to improvement in draft controls.

This is a continuation in part of my copending application Serial No. 332,235, filed April 29, 1940, for Draft controls, now Patent No. 2,253,290, dated August 19, 1941.

In the above entitled application there is illustrated and described a novel draft control for stoker-fired or other automatically controlled heating plants adapted to automatically increase the draft when the furnace or heating plant is in operation, being under the control of the automatic firing or other automatic controlling means; and to substantially diminish the draft during the "off" period of operation, thereby effecting substantial savings in fuel costs. In the operation of that control a stalling motor is employed, the current of which is regulated in accordance with the desired operation, said motor being operatively connected to the draft control gate through a drum and tension chain connected to the gate in such manner that the torque exerted thereon by the motor varies in the manner of an adjustable counterweight mounted on the gate.

In the present application, the main objects are:

First, to provide a draft control for the foregoing purposes wherein a uniformly energized motor is employed.

Second, to provide a control of the type described wherein the variation in the control torque effective on the gate is accomplished by adjusting the point of application of the torque thereto while at the same time insuring that this supplemental torque varies proportionately with the torque action of a counterweight on the gate.

Third, to provide a construction of the foregoing character which is exceedingly simple and inexpensive in its parts, yet very accurate and sensitive in its action.

Fourth, to provide a control of the type described which is readily embodied in existing furnace installations and which has provision for eliminating mechanical interference of its parts in operation.

Further objects relating to details and economies of my invention will appear from the description to follow. The invention is defined in the claims.

A structure embodying the features of my invention is illustrated in the accompanying drawing, wherein:

Fig. 1 is a fragmentary perspective view illustrating the control of my invention in operative

installed relation to a furnace or chimney breeching.

Fig. 2 is an enlarged fragmentary view in vertical longitudinal section illustrating the draft control housing and gate and other instrumentalities associated therewith for effecting the supplemental control of the gate in accordance with my invention, the motor control drum being arbitrarily shown for the purpose of clarity of illustration, in a different position from that ordinarily employed in practice.

Fig. 3 is a fragmentary view in horizontal section on line 3—3 of Fig. 2, illustrating the gate pivoting structure employed.

Fig. 4 is an enlarged fragmentary view illustrating a modified embodiment of a connection for the supplemental torque means to the gate operating in accordance with the principle of the present invention.

Fig. 5 is an enlarged fragmentary view in section on a line corresponding to line 5—5 of Fig. 4.

In my application Serial No. 332,235, I describe a draft control including a gate having an adjustable counterweight thereon to exert a relatively light gravitational torque on a control gate tending to close the same. The control of that application included a stalling motor developing a torque variable by relation to the current energizing the motor and controllable in accordance with the operation of an automatic firing or other control mechanism for the heating plant. This motor was connected by a tension chain to a projecting arm on the gate in such manner that the torque on the gate at any period in the operation of the motor varied proportionately with the torque exerted on the gate by the counterweight due to the gravitational force thereon. Such structure constitutes a control of a very great sensitivity capable of insuring a very low draft during periods of inoperation of the stoker or other firing instrumentality, which, however, is substantially increased when the instrumentality came into operation.

In accordance with the present invention I provide a control motor 1 enclosed in a suitable housing 2 secured by a bracket 3 to the draft control housing 4, which latter is suitably attached to the furnace flue or chimney breeching 5 for communication therewith. Instead of being controlled by varying the supply current or voltage therefor, the motor 1 receives a uniform 110 volt or 220 volt current at all times, being energized when the furnace firing or other control device comes into operation in a manner known to the art. During periods of inoperation of the

firing or control instrumentality, the motor 1 is de-energized.

In the present structure, the magnitude of the motor torque effective for the desired closing torque supplementary or implementary purpose is determined by the provisions to be described.

The reference numeral 6 designates the draft control gate of the present device, which is pivotally mounted on a trunnion 7 carried by an adaptor fitting 8 in the mouth of the control housing 4, this fitting having the control gate opening 9 therein with which gate 6 coacts to regulate the flow of air into the housing. Though the housing is circular in section, the opening is truncated at its sides by the provision of rearwardly extending wings 10 on fitting 8 and it will be understood that the gate is similarly truncated at its sides. The control housing opening is thus generally rectangular in outline.

The gate 6 is provided with a counterweight or balance mechanism consisting of the rear weight 11 attached to the inner side thereof and a further front adjustable counterweight 12 secured to an elongated forwardly extending rod 13 attached to the gate in line with weight 11. The counterweight 12 is manually adjustable on rod 13 and secured thereon by a set screw 14 or, alternatively, the counterweight may be adjustably threaded on the rod for positioning so that the counterbalance mechanism as a whole exerts a closing torque on the gate, being, however, preferably resistant, only to a very light draft pressure. Thus, the draft during the "off" period might be only .02 or .03 inch, or only slightly more than a zero draft setting. Alternatively the net counterbalancing torque by such means could in some installations be operative in the other direction. When the burner or other combustion or control instrumentality for the heating plant comes into operation, it is intended that the draft in the control housing be increased substantially and to any extent necessary, and to this end I provide the supplemental connections to the control motor 1 to be described to thereby variably increase the closing torque on the gate during "on" operation.

These supplemental provisions consist of a plate-like arm or bracket 15 secured to and projecting from the front side of the gate and provided with a row of apertures 16 for the reception of a wire, rod-like tension connector 17. This connector is secured at its other end to a flexible tension member or chain 18 wound on the drum 19 on motor 1.

It will be appreciated that in practice the counterbalance weight 12 is properly positioned on rod 13 having regard for the dead weight of connector 17 and chain 18 which are supported by the gate when the motor is not energized. In other words, the net or resultant of all the gravitational forces exerting torque on the gate is preferably such that a slight closing tendency is imparted thereto during "off" periods of the firing or control instrumentality, though the opposite is possible, so long as closing torque is applied by the motorized means during the "on" periods, such that the total effect on the gate is in the closing direction.

It will be noted with reference to Fig. 2, and it is of essential importance in the present invention, that the holes 16 are arranged along an arcuate or curved line. It is evident that the supplemental torque exerted on the gate by the motor 1 through the connector 17 will vary in magnitude in accordance with which hole the

connector rod 17 is engaged, for the length of the moment arm or torque arm of the force is thereby determined. Were the holes 16 arranged in a straight line, however, a variable would be introduced because of the different angle defined by theoretical lines extending respectively from the centers of two different holes to the gate pivot point 7 and from the center of the hole tangent to drum 19, the latter line being the line of force of the motor. The holes are therefore arranged in a curvilinear row or outline to compensate for and eliminate this variable factor. Thus it will be noted with reference to Fig. 2 that when the connector 17 is attached to the extreme end hole, the angle A is enclosed by a theoretical line from the center of the said extreme hole and the pivot 7 and by the line of force through the hole tangent to the drum. The line of force obviously is merely an extension of the center line of tension chain 18. Were the connector 17 inserted or attached in a hole, say five places further to the right in Fig. 2, the corresponding angle would be as shown and indicated by the character B. By reason of the curved disposition of the holes in the present device, angles A and B are equal, so that for any point of attachment of the motorized control to the gate arm 15 the supplemental torque on the gate, regardless of its amount, varies in the same manner due to angularity introduced in the operation of the gate.

The connector 17 is preferably offset rearwardly at 20 so as to clear the lower edge of the gate as the latter swings outwardly, for example, as illustrated in dotted lines in Fig. 2. A hook 21 is provided at the end of the offset in this connector for engagement with the holes 18. It will be understood that this special configuration of the connector 17 has no effect on the force exerted on the gate, which is the same as if a tensioning element, flexible or straight in its entirety, were employed. This hook may be readily twisted and removed from any given hole 16 for connection with another.

For the purpose of ease of illustration and to clarify the foregoing angular relationships, I have chosen to show the motor positioned with its axis parallel to the axis of the gate. However in practice it may be desirable to arrange the motor axis at ninety degrees of this position, in the manner shown in the above identified application. Such a disposition enables a self compensating travel of the tension chain on the motor drum to thereby minimize the tendency to depart from an exactly vertical pull. Provisions to this end are shown and described in said copending application.

The foregoing control is a very simple and inexpensive one and highly effective in operation. The torque for the gate varies in the same proportionate manner for the various gate positions, regardless of which hole the connector or link 17 is engaged with, being of course stronger when the latter is in a hole nearer the outer end of the gate.

As illustrated in solid lines in Fig. 2, the theoretical line X-Y drawn through the gate pivot and the point of attachment of the motor tensioned element 17 is approximately parallel to the axis of counterweight rod 13, hence the concept disclosed in my application Serial No. 332,235 of maintaining the variations in torque exerted by the motor proportional to the counterweight torque, regardless of the angular position of the gate, is also embodied in this appli-

cation. However, when connector 17 is attached to another of the holes 16, as for example the sixth hole from the left in Fig. 2, then L—M would be the theoretical line through said hole and the gate axis. This is evidently not parallel to the axis of rod 13, so that in this respect there is apparently a slight departure from the principle relied on in my aforesaid application. However, in practice the curvature of the row of holes may be less pronounced than as illustrated so as to achieve a balance between the factors of (a) approximate, if not exact, equivalency of the angles A, B; and (b) approximate, if not exact, parallelism of line L—M or X—Y with the counterweight rod 13. Thus to a great extent the fruits of both concepts may be secured. Wherever positioned, connector 17 will closely simulate in proportion the variations in the counterweight torque in the operation of the gate, and likewise the motor will be effective on the latter, throughout the swing of the gate and with the connector in one hole 16, in a manner closely approximating its action in another hole, though of course quantitatively different.

From the foregoing, it will be appreciated that in all cases the line of force exerted by the motor and corresponding to the center line of the chain is at the same angle to a line extending from the axis or pivot of the gate to the hole in which the link 17 is attached. Practical experience in operation has indicated that this angle, marked A or B in Fig. 2, should be somewhere between 110° and 115°. Accordingly rod 13 is arranged to extend downward at a similar angle. Hence the torque produced by the power of the motor and applied to the gate has the same effect thereon as that produced by the counterweight 12. The gravitational force on the counterweight 12 acts vertically, but the power of the motor can be applied in quite a number of directions and still be similar in its variation in effect to that of the counterweight. This adjustable connection of the motor to the gate considerably reduces the cost of the control. No rheostat or other current control means are required and the special gate arm and motor connector can be supplied at little cost.

In Figs. 4 and 5, I illustrate a slightly modified embodiment of the means for attaching the motor connector link to the gate, the link in this instance being indicated by the reference numeral 22. In this embodiment, a forwardly and downwardly curved arm or bracket 23 is secured to the gate 24 in any suitable manner, being provided with a similarly curved or arcuate slot 25. Adjustable in this slot is a headed clamp screw 26 through which an offset 27 of the link extends longitudinally, being maintained against separation by a cotter pin 28. Screw 26 threadedly receives the clamp nut 29 for securing the link in any desired position in the slot 25, it being understood that the link offset is freely pivotal in the axial opening in the screw receiving the same.

I have illustrated and described my improvements in embodiments which are very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. A draft control for an automatically fired furnace or boiler controlled by an automatic instrumentality, comprising a motor governed by said instrumentality, an open ended control housing communicating with the flue of the furnace or boiler and having a gate pivotally mounted thereon adjacent the opening to control the flow of air through the latter, a counterweight adjustably mounted on a downwardly extending arm secured to said gate, said counterweight normally exerting a relatively slight torque on the gate tending to swing the same toward closing position, and a supplemental torque applying bracket secured on and projecting outwardly from said gate and provided with a series of apertures arranged in a downwardly and outwardly curved outline, said motor having a winding drum provided with a flexible connector having removable and selective connection with one of said apertures whereby to regulate the amount of torque supplementary to the torque of said counterweight which is applied to the gate by said motor and connector, the curvature of said series of apertures being such that the line of force from the motor to any one thereof is at a predetermined substantially constant angle to a line from said aperture to the pivot of the gate, said counterweight supporting rod being arranged on said gate at a similar angle.
2. A draft control for an automatically fired furnace or boiler controlled by an automatic instrumentality, comprising a motor governed by said instrumentality, an open ended control housing communicating with the flue of the furnace or boiler and having a gate pivotally mounted thereon adjacent the opening to control the flow of air through the latter, a counterweight adjustably mounted on an arm secured to said gate, said counterweight normally exerting a relatively slight torque on the gate tending to swing the same toward closing position, and a supplemental torque applying bracket secured on and projecting outwardly from said gate and provided with a series of apertures arranged in a downwardly and outwardly curved outline, said motor having a connector having removable and selective connection with one of said apertures whereby to regulate the amount of torque supplementary to the torque of said counterweight which is applied to the gate by said motor and connector, the curvature of said series of apertures being such that the line of force from the motor to any one thereof is at a predetermined substantially constant angle to a line from said aperture to the pivot of the gate, said counterweight supporting rod being arranged on said gate at a similar angle.
3. A draft control for an automatically fired furnace or boiler controlled by an automatic instrumentality, comprising a motor governed by said instrumentality, an open ended control housing communicating with the flue of the furnace or boiler and having a gate pivotally mounted thereon adjacent the opening to control the flow of air through the latter, a counterweight adjustably mounted on an arm secured to said gate, said counterweight normally exerting a relatively slight torque on the gate, and a supplemental torque applying bracket secured on and projecting outwardly from said gate and provided with a series of apertures arranged in a curved outline, said motor having a connector having removable and selective connection with one of said apertures whereby to regulate the amount of torque supplementary to the torque

of said counterweight which is applied to the gate by said motor and connector, the curvature of said series of apertures being such that the line of force from the motor to any one thereof is at a predetermined substantially constant angle to a line from said aperture to the pivot of the gate.

4. A draft control for an automatically fired furnace or boiler controlled by an automatic instrumentality, comprising a motor governed by said instrumentality, an open ended control housing communicating with the flue of the furnace or boiler and having a gate pivotally mounted thereon adjacent the opening to control the flow of air through the latter, and a torque applying bracket secured on and projecting outwardly from said gate and provided with a series of apertures arranged in a curved outline, said motor having a connector having removable and selective connection with one of said apertures whereby to regulate the amount of torque applied to the gate by said motor and connector, the curvature of said series of apertures being such that the line of force from the motor to any one thereof is at a predetermined substantially constant angle to a line from said aperture to the pivot of the gate.

5. A draft control for an automatically fired furnace or boiler controlled by an automatic instrumentality, comprising a motor governed in its operation by said instrumentality, a control housing communicating with the flue of the furnace or boiler and having an opening and a gate pivotally mounted thereon adjacent the opening to control the flow of air through the latter, a counterweight adjustably mounted on a downwardly extending arm secured to said gate, said counterweight normally exerting a relatively slight torque on the gate tending to swing the same toward closing position, and a supplemental torque applying bracket projecting outwardly from said gate and apertured along a curved outwardly and downwardly extending line to adjustably receive a connector, said motor having a winding drum provided with a flexible connector having means for removable and selective connection with said gate bracket at the apertured portion thereof to regulate the amount of torque supplementary to the torque of said counterweight which is applied to the gate by said motor and connector, the curvature of said apertured line being such that the line of force from the motor to any desired point thereon is at a predetermined constant angle to a line from said one to the pivot of the gate, said counterweight supporting rod being arranged on said gate at a similar angle.

6. A draft control for an automatically fired furnace or boiler controlled by an automatic instrumentality, comprising a motor governed in its operation by said instrumentality, a control housing communicating with the flue of the furnace or boiler and having an opening and a gate pivotally mounted thereon adjacent the opening to control the flow of air through the latter, a counterweight adjustably mounted on a downwardly extending arm secured to said gate, said counterweight normally exerting a relatively slight torque on the gate, and a supplemental torque applying bracket projecting outwardly from said gate and apertured along a curved line to adjustably receive a connector, said motor having a winding drum provided with a connector having means for removable and selective connection with said gate bracket at the aper-

tured portion thereof to regulate the amount of torque supplementary to the torque of said counterweight which is applied to the gate by said motor and connector, the curvature of said apertured line being such that the line of force from the motor to any desired point thereon is at a predetermined constant angle to a line from said one to the pivot of the gate, said counterweight supporting rod being arranged on said gate at a similar angle.

7. A draft control for an automatically fired furnace or boiler controlled by an automatic instrumentality, comprising a motor governed in its operation by said instrumentality, a control housing communicating with the flue of the furnace or boiler and having an opening and a gate pivotally mounted thereon adjacent the opening to control the flow of air through the latter, and a torque applying bracket projecting outwardly from said gate and apertured along a curved line to adjustably receive a connector, said motor having a winding drum provided with a connector having means for removable and selective connection with said gate bracket at the apertured portion thereof to regulate the amount of torque applied to the gate by said motor and connector, the curvature of said apertured line being such that the line of force from the motor to any desired point thereon is at a predetermined constant angle to a line from said one to the pivot of the gate.

8. A draft control for an automatically fired furnace or boiler controlled by an automatic instrumentality, comprising a motor governed in its operation by said instrumentality, a control housing communicating with the flue of the furnace or boiler and having an opening and a gate pivotally mounted thereon adjacent the opening to control the flow of air through the latter, a torque applying bracket projecting outwardly from said gate and apertured along a curved line to adjustably receive a connector, and a motor connector connected to said motor having means for removable and selective connection with said gate bracket at the apertured portion thereof to regulate the amount of torque applied to the gate by said motor and connector, the curvature of said apertured line being such that the line of force from the motor to any desired point thereon is at a predetermined constant angle to a line from said one to the pivot of the gate.

9. A motorized draft control for an intermittently operating furnace or boiler controlled by an automatically operated instrumentality, comprising a control housing communicating with the flue of the furnace or boiler and having a swinging control gate pivotally mounted therein, counterweight means associated with said gate including an adjustable counterbalance and effective to exert a slight torque on the gate tending to swing the same to closing position, and means for supplementing the action of said counterweight means at certain periods, comprising a motor controlled by said instrumentality to come into operation when said instrumentality is operated, said motor having an actuating drum thereon, an outwardly extending bracket on said gate, and flexible tensioning means associated with and actuated by the motor drum and provided with a link connector having an outward offset therein to accommodate said gate in the swinging thereof, said connector being removably attachable to said bracket and the latter having curvedly disposed means for the selective reception of said connector at varying distances from the gate pivot, whereby

to provide different moment arms for the application of motor torque and whereby the line of force of the motor is at a predetermined constant angle to a line between the point of attachment of the connector and the pivot of the gate, regardless of the moment arm of the torque.

10. A motorized draft control for an intermittently operating furnace or boiler controlled by an automatically operated instrumentality, comprising a control housing communicating with the flue of the furnace or boiler and having a control gate pivotally mounted therein, counterweight means associated with said gate including an adjustable counterbalance and effective to exert a slight torque on the gate tending to swing the same to closing position, and means for supplementing the action of said counterweight means at certain periods, comprising a motor controlled by said instrumentality to come into operation when said instrumentality is operated, said motor having an actuating drum thereon, an outwardly extending bracket on said gate, and flexible tensioning means associated with and actuated by the motor drum and provided with a connector, said connector being removably attachable to said bracket and the latter having curvedly disposed means for the selective reception of said connector at varying distances from the gate pivot, whereby to provide different moment arms for the application of motor torque and whereby the line of force of the motor is at a predetermined constant angle to a line between the point of attachment of the connector and the pivot of the gate, regardless of the moment arm of the torque.

11. A motorized draft control for an intermittently operating furnace or boiler controlled by an automatically operated instrumentality, comprising a control housing communicating with the flue of the furnace or boiler and having a control gate pivotally mounted therein, counterweight means associated with said gate including an adjustable counterbalance and effective to exert a slight torque on the gate tending to swing the same to closing position, and means for supplementing the action of said counterweight means at certain periods, comprising a motor controlled by said instrumentality to come into operation when said instrumentality is operated, a bracket on said gate, and tensioning means associated with and actuated by the motor and provided with a connector, said connector being removably attachable to said bracket and the latter having curvedly disposed means for the selective reception of said connector at varying distances from the gate pivot, whereby to provide different moment arms for the application of motor torque and whereby the line of force of the motor is at a predetermined constant angle to a line between the point of attachment of the connector and the pivot of the gate, regardless of the moment arm of the torque.

12. A motorized draft control for an intermittently operating furnace or boiler controlled by an automatically operated instrumentality, comprising a control housing communicating with the flue of the furnace or boiler and having a control gate pivotally mounted therein, counterweight means associated with said gate effective to exert a torque on the gate tending to swing the same, and means for the action of said counterweight means at certain periods, comprising a motor controlled by said instrumentality to come into operation when said in-

strumentality is operated, a bracket on said gate, and tensioning means associated with and actuated by the motor and provided with a connector, said connector being removably attachable to said bracket and the latter having curvedly disposed means for the selective reception of said connector at varying distances from the gate pivot, whereby to provide different moment arms for the application of motor torque and whereby the line of force of the motor is at a predetermined constant angle to a line between the point of attachment of the connector and the pivot of the gate, regardless of the moment arm of the torque.

13. A motorized draft control for an intermittently operating furnace or boiler controlled by an automatically operated instrumentality, comprising a control housing communicating with the flue of the furnace or boiler and having a control gate pivotally mounted therein, counterweight means associated with said gate, and means for implementing the action of said counterweight means, comprising a motor controlled by said instrumentality to come into operation when said instrumentality is operated, said motor having an actuating drum thereon, a bracket on said gate, and flexible tensioning means associated with and actuated by the motor drum and provided with a connector removably attachable to said bracket, the latter having curvedly disposed means for the selective reception of said connector at varying distances from the gate pivot whereby to provide different moment arms for the application of motor torque and whereby the line of force of the motor is at a predetermined constant angle to a line between the point of attachment of the connector and the pivot of the gate, regardless of the moment of the torque.

14. A motorized draft control for an intermittently operating furnace or boiler controlled by an automatically operated instrumentality, comprising a control housing communicating with the flue of the furnace or boiler and having a control gate pivotally mounted therein, a motor controlled by said instrumentality to come into operation when said instrumentality is operated, said motor having an actuating drum thereon, a bracket on said gate, and flexible tensioning means associated with and actuated by the motor drum and provided with a connector removably attachable to said bracket, the latter having curvedly disposed means for the selective reception of said connector at varying distances from the gate pivot whereby to provide different moment arms for the application of motor torque and whereby the line of force of the motor is at a predetermined constant angle to a line between the point of attachment of the connector and the pivot of the gate, regardless of the moment of the torque.

15. A motorized draft control for an intermittently operating furnace or boiler controlled by an automatically operated instrumentality, comprising a control housing communicating with the flue of the furnace or boiler and having a control gate pivotally mounted therein, a motor controlled by said instrumentality to come into operation when said instrumentality is operated, a bracket on said gate, and means associated with and actuated by the motor including a connector removably attachable to said bracket, the latter having curvedly disposed means for the selective reception of said connector at varying distances from the gate pivot

whereby to provide different moment arms for the application of motor torque and whereby the line of force of the motor is at a predetermined constant angle to a line between the point of attachment of the connector and the pivot of the gate, regardless of the moment of the torque.

16. In a draft control of the type described, a control housing having a gate pivotally mounted thereon, the lower edge of said gate being swing-

able substantially outwardly in the operation thereof, a motorized control for the gate including a motor having a flexible actuating element, and a link connector from said element to a bracket on the front of the gate, said link connector being disposed in front of said gate and having a substantial offset therein to receive and accommodate the lower edge of said gate in said outward swinging movement of the latter.
